ABSTRACT OF THE DISCLOSURE

Octadienyl esters are prepared by reacting butadiene with carboxylic acids in the presence of palladium catalysts, preferably complexed with phosphite or phosphine ligands, and tertiary amines having a basicity constant K_b greater than 10^{-7} as reaction modifiers. The tertiary amines also assist in the separation of the products.

This invention relates to an improved process for making octadienyl esters.

It is already known to produce octadienyl esters by the simultaneous dimerization and reaction of butadiene with carboxylic acids in the presence of palladium or platinum catalysts. A process of this nature is described in J. E. McKeon and D. R. Bryant application Ser. No. 660,226, filed Aug. 14, 1967 now U.S. Pat. No. 3,534,088, and more particularly, one which is carried out in the presence of a source of carboxylate ion, such as potassium or sodium acetate. While this is a useful process, the yields of octadienyl esters and the rate of reaction are lower than are commercially desirable.

It has been found that a marked improvement in the process can be obtained if it is carried out in the presence of a tertiary amine. Such amines have three significant effects on the reaction: they increase the rate of reaction at equivalent temperatures, they markedly increase the conversion of butadiene, and they improve the efficiency of the reaction to octadienyl esters. These effects of the amines, in addition to being a source of carboxylate ion, shown to be beneficial by McKeon and Bryant, may be attributed to their forming complexes with the palladium catalyst leading to a more active catalyst. On the other hand, sodium and potassium acetate are incapable of forming complexes with palladium catalysts.

A representative number of tertiary aliphatic amines have been investigated and all significantly enhance the activity of the palladium catalyst. Thus, effective amines include trimethylamine, triethylamine, triisopropylamine, tributylamine and the like; oxygen-substituted tertiary amines, such as N-methylmorpholine, 2-dimethylaminoethanol, 2-dimethylaminoethylacetate, 2-diethylaminoethanol, methyldiethanolamine, triethanolamine and 3-dimethylamino-1-propanol; and tertiary diamines, such as N,N,N',N'-tetramethyl-1,3-propanediamine, N,N,N',N'-tetramethyl-1,3-butanediamine, N,N,N',N'-tetramethyl-ethylene diamine and triethylene diamine. Weakly basic aromatic amines, such as pyridine, having a basicity constant, $K_b = 1.4 \times 10^{-9}$, have been shown to be ineffective in increasing the activity of the catalyst, and it is therefore believed that all tertiary amines having a basicity equivalent to the tertiary aliphatic amines mentioned above would be effective in the process of this invention (i.e., benzylpyrrolidine). Thus, tertiary amines having a basicity constant K_b greater than 10^{-7} , and preferably in the range of 10^{-3} to 10^{-6} , are preferred in the practice of the invention.

As mentioned in the McKeon and Bryant patent application Ser. No. 660,226, the reaction of butadiene with acetic acid according to the present invention is fundamentally different from the olefin-acetic acid reactions

described in U.S. Pat. No. 3,221,045 issued to J. E. McKeon and P. S. Starcher, and the only similarity is in the reference to palladium catalysts. Thus, the presence of a catalytic co-oxidant, i.e., Cu(II), is not necessary for the butadiene dimerization reaction of the present invention, and if present, greatly favors the formation of butenyl esters, rather than the octadienyl esters.

The butadiene dimerization and addition reaction of this invention differs from that described in U.S. Pat. No. 3,221,045, not only in that catalytic co-oxidant is not needed in the process of this invention, but also in that the reactions of this invention are carried out under non-oxidizing conditions and no water is produced in the process. For example, the reaction of ethylene, oxygen, and acetic acid to produce vinyl acetate may be written as follows:

On the other hand, the butadiene reaction of this invention may be represented as follows:

As shown in the equations above, all the hydrogen atoms present in the two molecules of butadiene and the molecule of acetic acid appear in the final octadienyl acetate; none is oxidized to water.

As previously mentioned, it is important to carry out the reaction under non-oxidizing conditions. Oxygen is not required to support the butadiene dimerization and addition reaction of this invention, but is also deleterious, if present in significant amounts. Thus, in the presence of oxygen, the starting 1,3-dienes readily form peroxides, as do the octadienyl ester products. Such peroxides lead to undesired radical induced polymerization reactions, and resulting low yields, if any, of the desired products. Oxygen also has an unfavorable effect on the phosphorus containing ligands, which are often included in the palladium catalyst, leading to the oxidation of P(III) to P(V) yielding phosphine oxides and phosphates which are ineffective in promoting the palladium catalysts.

The octadienyl esters formed in the process of this invention are primarily 2,7-octadien-1-ol acetate, although small amounts of the secondary acetate, 1,7-octadiene-3-ol acetate, are also formed. Upon hydrogenation and hydrolysis, the primary acetate is readily converted to octanol-1, which is desirable for making diethyl phthalate, an important plasticizer. The secondary acetate can also be converted to the alcohol by hydrogenation and hydrolysis, although secondary alcohols are less desirable for making plasticizers. However, such secondary alcohols can be converted to useful nonionic surfactants by reaction with ethylene oxide.

The use of the tertiary amines as catalyst modifiers has also provided an unexpected benefit in the separation process. At the conclusion of the reaction, the volatile products are stripped from the crude reaction mixture, leaving a catalyst residue for recycle to the reactor. In distilling the volatile products, it would normally be expected that the primary ester and the secondary ester would distill together since their boiling points are close together. However, it has been found that the secondary ester first distills over as an azeotrope with the tertiary amine and with the tertiary amine-acetic acid azeotrope, leaving the purified primary ester as a residue or as a second distillate, if there is enough amine present to form azeotropes with all of the secondary ester.

When the novel process is conducted as a homogeneous, liquid phase reaction, the active catalyst species can be derived from a palladium compound which is soluble in the reaction mixture or which can become

soluble therein by reaction with one of the components of said mixture. Illustrative palladium compounds which may be used include palladium(II) alkanoates, e.g., palladium(II) acetate, palladium(II) propionate, palladium(II) butyrate, palladium(II) hexanoate, and the like; the palladium(II) cycloalkanecarboxylates, e.g., palladium(II) cyclohexanecarboxylate, and the like; palladium(II) aryl carboxylates, e.g., palladium(II) benzoate, palladium(II) monomethyl phthalate and the like; olefin complexes of palladium, 1,5-cyclooctadiene palladium(II) chloride, π -allylpalladium acetate, endo-dicyclopentadienepalladium(II) bromide and the like; complexes with alkyl and aryl nitriles, e.g., bis(benzonitrile)palladium(II) chloride, bis(propionitrile)palladium(II) cyanide, and the like; palladium(II) bromide, palladium(II) nitrate, palladium(II) sulfate, palladium(II) acetylacetone, ammonium chloropalladate, ammonium chloropalladite, potassium bromopalladite, dichlorodiamminepalladium(II), dinitritoamminepalladium(II), potassium chloropalladate, potassium chloropalladite, sodium chloropalladite, and the like; complexes of palladium with trihydrocarbylphosphines and arsines, e.g.,

bis(triphenylphosphine)palladium(II) acetate, tetrakis(triphenylphosphine)palladium(0), tetrakis(dimethylphenylphosphine)palladium(0), bis(triphenylphosphine)palladium(II) nitrate, bis(triptynarsine)palladium(II) chloride, bis(dimethylphenylphosphine)palladium(II) chloride, bis(tributylarsine)palladium(II) bromide, bis(triptylphosphine)palladium(II) nitrate, bis(triphenylphosphine)palladium(II) carbonate

and the like; complexes with phosphates and phosphites, e.g., bis(triptylphosphite)palladium(II) nitrate; bis(triphenylphosphate)palladium(II) chloride, and the like; complexes with bidentate ligands of the types outlined above may also be used.

Palladium metal in an active form such as palladium black or palladium on a support, such as charcoal, may be used as the source of the catalytic palladium species. Palladium complexes can be generated in situ by reaction of such active forms of palladium with species such as allyl bromide (to give π -allylpalladium bromide) or trihydrocarbyl phosphines.

In addition to the palladium compounds listed, the analogous compounds of platinum are well known and are also effective as catalysts in the process of the invention.

While any one of the palladium or platinum compounds previously described can be used as catalysts, improved results can be obtained by the addition of catalyst modifiers.

The modifiers can be selected from the trihydrocarbyl phosphines (the trialkylphosphines; e.g., tri-n-octylphosphine, tributylphosphine, dimethyl-n-octylphosphine and the like; triarylphosphine, e.g., triphenylphosphine, tri-tolylphosphine, and the like; the tertiary alkarylphosphines, e.g., diphenylethylphosphine, dimethylphenylphosphine, bis(diphenylphosphino)methane, 1,2-bis(diphenylphosphino)ethane and the like, the trihydrocarbylarsines (the trialkyl, triaryl and alkaryl arsines illustrated by substitution of As for P in the compounds described above) and the trihydrocarbylphosphites (trialkylphosphites, e.g., triethylphosphite, tributylphosphite, tri(2-ethylhexyl)phosphite, tris(2-ethoxyethyl)phosphite and the like; triarylphosphites, e.g., triphenylphosphite, tri(p-chlorophenyl)phosphite, tri(1-naphthyl)phosphite, triorthophenylene diphosphite, and the like. Mixed alkarylphosphites can be prepared and used. Because of the methods of syntheses and the relatively facile exchange of groups, it is difficult to prepare discrete compounds in high yield; the mixtures are suitable for use as modifiers if desired.

Because of considerations such as solubility, it may be advantageous to use mixtures of different hydrocarbyl-

phosphines, for example, or mixtures of phosphines and/or arsines and/or phosphites.

Compounds with both phosphorus to oxygen and phosphorus to carbon bonds, such as diethoxyphenylphosphine [$(C_2H_5O)_2P-Ph$], ethoxydiphenylphosphine, dimethoxyphenylphosphines, diphenoxyethylphosphine, diethoxybutylphosphine, and the like are also useful as catalyst modifiers.

Other phosphorus compounds which are useful in the reaction are bicyclic phosphites which include compounds of the general formula

in which R can represent a hydrogen; or an alkyl group, such as methyl, ethyl, isopropyl, nonyl, and the like; or an aryl group such as phenyl, tolyl, naphthyl, and the like; or a functionally substituted alkyl, such as hydroxymethyl, ethoxymethyl, phenoxyethyl, hydroxyethyl, hydroxypentyl, acetoxyethyl, acetoxypentyl and the like. These phosphites can be visualized as being derived as the products of esterification of phosphorus acid ($(HO)_3P$) with triols of the general formula $R-C-(CR'OH)_3$ where R' is either hydrogen or some carbon containing radical.

Another type of bicyclic phosphite that is useful as a catalyst modifier includes those compounds of the general formula shown below:

In this instance, R and R' can be hydroxyl, hydrogen, alkyl, aryl, alkyloxy, aryloxy and the like as illustrated for the R group of the bicyclic phosphites described above.

These modifiers may be added to the reaction mixture in quantities such that the ratio of the total number of moles of modifiers of all kinds (whether added as part of the palladium or platinum catalyst or added separately) to palladium or platinum, can vary, for example, from 200:1 and higher and 1:10 and lower, preferably from 100:1 to 1:1, mostly preferably 20:1 to 1:1.

The catalyst is employed in catalytically significant quantities. A palladium concentration in the range from about 0.00000 molar and lower to about 1 molar and higher is suitable. A catalyst concentration in the range from about 0.0001 to about 0.1 molar is preferred. For optimum results the nature of the reactants, the operative conditions of the reaction, the solvent characteristics of the carboxylic acid and amine employed (and any inert normally liquid organic diluent, if employed) and other factors will largely determine the desired catalyst concentration.

The catalyst is a combination of the active transition metal (e.g., palladium) and a ligand such as a P or As compound as previously described. These catalysts can be formed in situ or preformed and charged to the reaction initially.

The carboxylic acids which are contemplated in this novel process contain at least one carboxy group, i.e., $-COOH$. Illustrative examples of these carboxylic acids are acetic acid, chloroacetic acid, propionic acid, butyric acid, isobutyric acid, valeric acid, hexanoic acid, heptanoic acid, dodecanoic acid and the like; the cycloalkanecarboxylic acids, e.g., cyclohexanecarboxylic acid, and cyclopentanecarboxylic acid and the like; aromatic acids such as benzoic acid, naphthoic acid, phenylacetic acid and the like; and monocarboxylic acids with carbon-carbon unsaturation such as acrylic acid, butenoic acid, oleic acid, undecenoic acid, cinnamic acid, sorbic acid, and the like; half acid esters or half dialkylamides of dicarboxylic acids; as well as the dicarboxylic acids themselves, such as malonic acid, adipic acid, azelaic acid, phthalic acid, isophthalic and/or terephthalic acid and the like.

The direct use of dibasic acids, such as phthalic acid,

provides an interesting embodiment of the invention in that it is possible to synthesize the dioctadienyl phthalates, which can be hydrogenated under mild conditions to give dioctyl phthalates, the desired plasticizers, directly. This avoids the hydrolysis step in the recovery of the octadienols from the actadienyl esters which has been previously discussed. In the hydrogenation of the dioctadienyl phthalates, the olefinic bonds in the alcohol residue are hydrogenated much more readily than the aromatic double bonds, and the hydrogenation can readily be carried out under known conditions using typical hydrogenation catalysts, such as Raney nickel.

In the general reaction, butadiene may be replaced with other 1,3-dienes to form substituted octadienyl esters. Suitable 1,3-dienes include isoprene, piperylene and 1,3-hexadiene.

A special effect of the tertiary amine modifiers is noted in the reaction of butadiene with acrylic acid. In this instance, the competing effect of the Diels-Alder reaction of butadiene with acrylic acid is possible, and, indeed occurs to a significant extent in the absence of a tertiary amine. However, in the presence of the tertiary amine, the dienophile function of the acrylic acid is reduced, and only negligible amounts of the Diels-Alder product are produced.

The octadienyl acrylates formed are again mixtures of 1-octa-2,7-dienyl acrylate with smaller amounts of 3-octa-1,7-dienyl acrylate. These are useful monomers for making acrylic polymers and copolymers with ethyl acrylate, which can be cross-linked through the double bonds of the alcohol residue to form insoluble polymers. These doubly unsaturated acrylates can also be copolymerized with ethylene to form cross-linkable polyethylenes of improved stiffness and durability. They can also be brominated and used in polyester formation of increase the fire resistance of the products.

The reactions of the present invention can be carried out by charging the carboxylic acid, the amine, the palladium compound, and the ligand modifier to a suitable pressure vessel and introducing butadiene. Other orders of addition of the reactants are also effective. The reaction can be carried out at -5° to 200° C. although the temperature of the reaction is not a critical part of the invention. Preferred reaction temperatures are 20° to 180° and most desirably from 50° C. to 125° C. The reaction can be carried out at autogeneous pressures or higher if desired. Reaction can also be observed at atmospheric pressure and below.

The rate and yields of the reactions are affected by the relative concentration of acid and amine with the maximum rates and efficiencies being obtained when near equimolar ratios of amine to carboxylic acid are used. The effect of butadiene concentration on the reaction rate and efficiency is found to be dependent on the amine to carboxylic acid ratio, but in general the rate increases as the relative amount of butadiene increases. The molar ratio of

amine can vary from 50 to 0.1 mole of carboxylic acid per atom of N in the added amine, but the preferred range is 10 moles to 0.3 mole of carboxylic acid per atom of N in the amine.

The ratio of butadiene to carboxylic acid can vary widely but the more butadiene present relative to the carboxylic acid the faster the rate of reaction. The ratio of butadiene to carboxylic acid can vary from 0.01-50 moles of butadiene per mole of carboxylic acid with a ratio of 0.2-8.0 moles of butadiene per mole of carboxylic acid being preferred.

Purified butadiene need not be used and instead the C₄ stream from an olefin plant, the usual feed to a butadiene refinery, can be employed in the reaction. This C₄ stream is a mixture of butadiene and butenes with smaller amounts of other hydrocarbons. When using such a stream, the molar ratios of diene to acid and acid to amine are still applicable to the invention as are the limitations on palladium concentration levels. No products are observed that could be interpreted as coming from the reaction of butenes with the carboxylic acid under these non-oxidizing conditions. This is further proof that this invention is fundamentally different from the olefin-acetic acid reactions described in U.S. Pat. No. 3,221,045 issued to J. E. McKeon and P. S. Starcher.

EXAMPLES

Experimental techniques

Two sizes of reactors were used in these experiments. Small runs were made in 50 cc. Pyrex pressure tubes to which the reactants were charged and the tubes capped with an ordinary bottle capper. Some caps were equipped with heavy rubber seals and holes through which samples could be removed using a syringe. These runs were made with intermittent agitation in an oil or water bath preheated to the desired temperature.

Larger runs were made in a three pint size Chemco glass reactor equipped with a mechanical stirrer. The reactants were charged and were heated by passing steam or hot water through an internal heating coil. This reactor was also equipped with a dip tube so that samples could be removed during the reaction for analysis by vapor phase chromatography (VPC).

Identification

Compounds made in this work were isolated by distillation and their structures confirmed by nuclear magnetic resonance spectroscopy, infrared spectroscopy, and elemental analysis. Once the structure of a compound was firmly established, it was identified in subsequent runs by its VPC retention time. The following tables are self-explanatory and the experiments are intended as examples of the invention but are not intended to necessarily illustrate the limitations of the invention.

In the abbreviations in the tables Pd(AcAc)₂ stands for palladium acetylacetone and Ph₃P stands for triphenyl phosphine.

Examples 49 and 50 (isobutyric and propionic acid)

Similar experiments with propionic acid and isobutyric acid were run by charging 0.20 moles of butadiene, 0.10 moles of the carboxylic acid, 0.027 moles of N,N,N',N'-tetramethyl 1,3-butanediamine, 0.25 mmoles of palladium acetylacetone, and 0.25 mmoles of triphenylphosphine to a 50 cc. Pyrex pressure tube and reacting at 90° for 1 hour. Both acids gave about 80 percent yields of the corresponding octadienylcarboxylates and improved rates and selectivity were observed relative to runs without the amine present. In both cases the butadiene conversion was 90%. The properties of these new compounds are given below:

NMR data is given in Table V.

1-octa-2,7-dienylpropionate

Analysis.—Calcd. for C₁₁H₁₈O₂ (percent): C, 72.49; H, 9.95. Found (percent): C, 72.38; H, 9.68. n_{D}^{20} , 1.4478.

3-octa-1,7-dienylpropionate

Analysis.—Calcd. for C₁₁H₁₈O₂ (percent): C, 72.49; H, 9.95. Found (percent): C, 72.50; H, 10.09. n_{D}^{20} , 1.4394.

1-octa-2,7-dienylisobutyrate

Analysis.—Calcd. for C₁₂H₂₀O₂ (percent): C, 73.44; H, 10.27. Found (percent): C, 73.31; H, 10.03. n_{D}^{20} , 1.4451.

3-octa-1,7-dienylisobutyrate

Analysis.—Calcd. for C₁₂H₂₀O₂ (percent): C, 73.44; H, 10.27. Found (percent): C, 73.77; H, 10.10. n_{D}^{20} , 1.4383.

Similar experiments without amine present resulted in a butadiene conversion of only 67 percent after 20 hours of reaction at 90° C.

Example 51 (benzoic acid)

To a 50 cc. Pyrex pressure tube were charged 0.1 moles of butadiene, 0.05 moles of benzoic acid, 0.05 moles of N,N,N',N'-tetramethyl-1,3-butanediamine, 0.25 mmoles of palladium acetylacetone, and 0.25 mmoles of triphenylphosphine. The tube was capped and heated to 80° C. for 5 hours, resulting in a 75% conversion of butadiene and a yield of 68.2% octadienyl-benzoate and 31.8% of 1,3,7-octatriene. When 0.12 moles of butadiene, 0.05 moles of benzoic acid, and 15 cc. of acetone, 0.25 mmoles of palladium acetylacetone, and 0.25 mmoles of tri-

phenylphosphine were reacted at 90° C. for 20 hours, 80% of the butadiene was converted and the yield of octadienyl-benzoates was 63.3%, while that of octatriene was 36.7%. Thus, the use of the amine modifier had increased the rate of reaction about four times and improved the yields of desired products.

Example 52 (acrylic acid)

To a glass-lined, two-liter, stirred Paar autoclave were charged 270 grams (5.0 moles) of butadiene, 360 grams (5.0 moles) of acrylic acid, 450 grams (4.5 moles) of N-methyl-morpholine, 3.3 grams (11 mmoles) of palladium acetylacetone, and 3.0 grams (11 mmoles) of triphenylphosphine. This mixture was maintained at 80-90° C. for 3.5 hours to yield 1091 grams of liquid product. This exact procedure was repeated to give another 1038 grams of liquid product. The runs were combined and 2 grams of hydroquinone added as an inhibitor. VPC analysis on a 6-ft. silicone rubber column indicated the presence of 166 grams of 3-octa-1,7-dienylacrylate and 357 grams of 1-octa-2,7-dienylacrylate representing a total yield of 53 percent. The liquid product was then stripped through a molecular still to remove the majority of the product from the catalyst. A "residue" of 328 grams was left. The distillate was charged to a 3/4" x 18" Vigreux still and a small amount of dimethylglyoxime added and then distilled at reduced pressure to yield 668 grams of a fraction, boiling point: 84-133/9-3.3 mm., that was a mixture of octadienylacrylates and the N-methylmorpholine salt of acrylic acid. The "heart" cuts, 418 grams, were combined and water washed several times until the VPC peaks representing impurities were removed. This resulted in 229 grams of a mixture of 27 percent 3-octa-1,7-dienylacrylate and 73 percent 1-octa-2,7-dienylacrylate, boiling point 85-87°/1.3 mm. The structure of the mixture was confirmed by IR and NMR spectroscopy.

NMR data on both isomers is given in Table V.

There were charged to a glass-lined, 3-liter, stainless steel autoclave 180 grams (3.3 moles) of butadiene, 240 grams (3.3 moles) of acrylic acid, 300 grams (3.0 moles) of N-methylmorpholine, 2.2 grams (7.2 mmoles) of palladium acetyl acetone and 2.0 grams (7.6 mmoles) of triphenylphosphine. This mixture was heated to 80° within 50 minutes and was maintained at 80-90° for 2.5 hours. The reaction product weighed 696 grams and VPC analysis indicated the presence of 103 grams of 1-octa-2,7-dienylacrylate and 47 grams of 3-octa-1,7-dienylacrylate, representing a 50 percent yield. The product was diluted with water and extracted with ether and the combined ether layers were washed three times with water. After removal of the ether, the residual material, 154 grams, was distilled at reduced pressure. A fraction, 44 grams, boiling point 47-55/0.6 mm. was obtained. VPC analysis indicated that the octadienylacrylate isomers were contaminated, probably by the N-methylmorpholine salt of acrylic acid. After several water washes this material was removed. The octadienylacrylate was distilled yielding a mixture that was 90 percent 3-octa-1,7-dienylacrylate.

NMR data on the product is given in Table V.

Data on C₁₁H₁₆O₂ (B. pt., 61-62°/0.8 mm.); percent: C, 73.38; H, 8.94. Calcd. for C₁₁H₁₆O₂ percent: C, 73.3; H, 9.0.

Example 53 (phthalic acid)

A mixture of 6.0 grams of butadiene, 3.3 grams of phthalic acid, 1.4 grams of N,N,N',N'-tetramethyl-1,3-butanediamine, 10 milliliters of N,N-dimethylacetamide, 0.076 gram of palladium acetylacetone and 0.060 gram of triphenylphosphite were heated to 90° for two hours. The product was treated with water and extracted with isopropylether. The ether layer was washed with 10 percent hydrochloric acid followed by washing with a saturated solution of sodium bicarbonate. This organic layer then contained only the by-product octatriene and the

diester present—bis(octadienyl)phthalate. The solution was hydrolyzed with a 25 percent potassium hydroxide solution to yield octadienol.

Example 54 (separation of products by azeotropic distillation)

An overhead product from a stripped reaction mixture analyzed as follows: 5.4% acetic acid, 3.5% octatriene, 16.5% tetramethylbutanediamine, 18.5% 3-acetoxy-1,7-octadiene (3-OAc) and 56.1% 1-acetoxy-2,7-octadiene (1-OAc). This mixture (984 grams) was fractionated using a 4-ft. x 1-in. packed "grapenut" distillation column. The distillation is summarized below:

Cut No.	Wt. of cut (g.)	B.P./mm.	Area percent from thermal detector VPC			
			Hg.	HOAc	Amine	3-OAc
1	84	30-55/4	4.6	35.4	31.5	-----
2	90.5	55-60/4	14.4	27.7	58.4	1.5
3	62	60-61/4	9.1	32.4	57.4	1.1
4	69	60-61/4	11.6	29.3	59.1	-----
5	18.5	60-62/4	5.0	65.8	28.9	0.3
6	47.5	60-62/3.5	10.6	40.7	40.3	8.4
7	40	62-63/3.5	16.9	30.2	6.1	46.8
8	34	62-64/3.0	21.9	19.6	1.6	59.9
9	148	62-64/3.0	23.1	18.7	1.1	57.3
10	362.5	65-68/2.0	-----	-----	.5	99.5

The products were cleanly sprung from amine and acetic acid by the addition of water. The water insoluble products were separated from the water layer, washed again with water and dried over sodium sulfate.

It will be noted that the 3-isomer distilled over with the amine as an azeotrope, leading to the recovery of the 1-isomer practically free of the secondary ester.

Example 55 (platinum catalyst)

The following experiment was run according to the capped tube technique previously described. The charge was platinum acetylacetone (0.25 mmole), triphenylphosphine (0.25 mmole), butadiene (0.2 mole), acetic acid (0.1 mole) and N,N'-tetramethyl-1,3-butanediamine (0.03 mole). These materials were reacted at 90° C. for 18 hours to give an 88% conversion of butadiene. The product was 6% 1,3,7-octatriene, 27.3% 3-acetoxy-1,7-octadiene and 66.7% 1-acetoxy-2,7-octadiene.

What is claimed is:

1. Process for converting butadiene to octadienyl esters which comprises reacting butadiene under non-oxidizing conditions with a carboxylic acid in the presence of a palladium or platinum catalyst and a tertiary amine having a basicity constant K_b greater than 10⁻⁷ and recovering said octadienyl esters from the reaction products, said carboxylic acid being selected from the group consisting of aliphatic and aromatic mono- and dicarboxylic acids and the ratio of carboxylic acid to tertiary amine being from 10 moles to 0.3 mole of carboxylic acid per atom of nitrogen in the amine.

2. Process for converting butadiene to octadienyl esters which comprises reacting butadiene under non-oxidizing conditions with a carboxylic acid in the presence of a palladium or platinum catalyst and a tertiary aliphatic amine, and recovering said octadienyl esters from the reaction products, said carboxylic acid being selected from the group consisting of aliphatic and aromatic mono- and dicarboxylic acids and the ratio of carboxylic acid to tertiary amine being from 10 moles to 0.3 mole of carboxylic acid per atom of nitrogen in the amine.

3. Process as claimed in claim 2 in which the carboxylic acid is acetic acid.

4. Process as claimed in claim 2 in which the carboxylic acid is acrylic acid.

5. Process as claimed in claim 2 in which the tertiary aliphatic amine contains oxygen bonded to carbon.

6. Process as claimed in claim 2 in which the amine is an aliphatic tertiary diamine.

7. Process as claimed in claim 2 in which the amine is triethylamine.

13

8. Process as claimed in claim 2 in which the amine is dimethylethanolamine.
9. Process as claimed in claim 2 in which the amine is N-methylmorpholine.
10. Process as claimed in claim 2 in which the amine is triethylenediamine. 5
11. Process as claimed in claim 2 in which the amine is N,N,N',N'-tetramethyl-1,3-butanediamine.
12. Process as claimed in claim 2 in which the catalyst is a palladium compound complexed with a phosphite ligand. 10
13. Process as claimed in claim 2 in which the catalyst is a palladium compound complexed with a phosphine ligand.
14. Process as claimed in claim 12 in which the phosphite ligand is triphenyl phosphite. 15

15. Process as claimed in claim 12 in which the phosphite ligand is trimethylolpropane phosphite

16. Process as claimed in claim 13 in which the phosphine ligand is triphenyl phosphine. 25
17. Process as claimed in claim 12 in which the palladium compound is palladium acetylacetone.

14

18. Process as claimed in claim 12 in which the palladium compound is palladium acetate.
19. Process as claimed in claim 13 in which the palladium compound is palladium acetylacetone.
20. Process as claimed in claim 13 in which the palladium compound is palladium acetate. 10
21. Process as claimed in claim 13 in which the catalyst is tetrakis(triphenylphosphine) palladium (O).
22. Process as claimed in claim 13 in which the catalyst is bis(triphenylphosphine) palladium carbonate.
23. Process as claimed in claim 2 in which the carboxylic acid is a phthalic acid.
